ARROW ADAPTER FOR SLINGSHOTS

Alton W. Hutson, Richmond, Calif.

Application October 13, 1950, Serial No. 189,935

7 Claims. (Cl. 124—20)

1

The present invention relates to improvements in an arrow adapter for a sling shot, and its principal object is to provide an adapter which may be easily applied to a sling shot frame so as to allow the latter to be used for shooting an arrow.

More particularly it is proposed in the present invention to arrange the adapter in such a manner as to provide a seat for the arrow and so as to make the seat adjustable for movement between an active position and a retracted position.

It is further proposed to provide two different forms of an arrow adapter, each capable of being used independently of the other, but also arranged in such a manner that they may be used in combination, with the seats for the arrow lined up, while each of the adapters serves to strengthen and steady the other.

Further objects and advantages of my invention will appear as the specification proceeds, and the novel features of my invention will be fully defined in the claims attached hereto.

The preferred forms of my invention are illustrated in the accompanying drawing, in which

Figure 1 shows a front view of one form of arrow adapter attached to a sling shot frame,

Figure 2, an edge view of the form shown in Figure 1,

Figure 3, a front view of a modified form of adapter as applied to a sling shot frame,

Figure 4, an edge view of the form shown in Figure 3,

Figure 5, a top view of the form shown in Figure 1,

Figure 6, a top view of the form shown in Figure 3,

Figure 7, a front view showing the two forms of adapter used in combination on the sling shot frame, and

Figure 8, an edge view of the combination shown in Figure 7.

While I have shown only the preferred forms of my invention, I wish to have it understood that various changes and modifications may be made within the scope of the claims attached hereto without departing from the spirit of the invention.

Referring first to the form illustrated in Figures 1, 2 and 5, the frame 1 is preferably made of a flat piece of wood comprising a body section 2, a handle 3, and two legs 4 projecting from the body section in spaced relation to one another, and in a direction opposite to that of the handle 3.

The two legs are spaced sufficiently to form a

2

rather large recess 5 adapted to allow the body of a sling to freely pass therethrough when the device is used as a sling shot for projecting a pebble or the like. The ends of the sling, indicated at 6, may be secured upon the ends of the legs by means of the slits 6' provided in the upper ends of the latter. The sling is usually made of rubber or similar elastic material, and the slits 6' are made somewhat narrower than the thickness of the sling material so that the ends of the sling may be introduced into the slits upon stretching the sling material and will automatically anchor themselves upon being released.

The frame as hereinabove described is more or less conventional in construction, and the present invention is directed principally to the adapter 7 intended to be used in combination with the frame.

The adapter comprises a stem 8 adapted to lie flat against the side of the frame and an enlarged body portion 9 having an arrow seat 10 arranged in the upper end thereof. The stem is formed with a slot 11 running lengthwise of the latter and may be secured upon the side face of the frame by means of a screw 12 extending through the frame and the slot 11, and a wing nut 13 threaded upon the screw. The slot allows the stem to be secured upon the side face of the frame in any desired position. In the position shown the arrow seat 10 is substantially in alignment with the outer ends of the legs 4 and may be used for the propulsion of an arrow by means of the sling. If it is desired to use the sling shot for projecting an ordinary missile such as a pebble or marble, the adapter 7 may be retracted upon loosening the wing nut 13, and secured in retracted position so as to clear the upper portion of the recess 5.

In the form shown in Figures 3, 4 and 6, the adapter comprises a band 14 of semi-rigid material slidable on the two legs 4 and a screw 15 passing centrally through opposing stretches of the band, with a wing nut 16 operable on the screw to draw the strands toward one another as shown in Figure 6 tightening the band upon the legs. The band carries an arrow seat 17 on one of its strands, midway of the legs of the frame, and by proper manipulation and positioning of the band along the legs the seat may be brought into registry with the upper ends of the legs or may be retracted to an out-of-the-way position in the bottom of the recess 5.

While the two forms shown and described thus far may be used individually, they may also be

used in combination so as to cause each to strengthen and reinforce the other.

This combination is illustrated in Figures 7 and 8. In this form the adapter 7 is secured upon one side of the frame as described before, and the band 14 is also applied in the manner previously described, the only additional feature being that the screw 15 of the band is also made to pass through the slot 11 of the stem of adapter 7 before the wing nut 16 is applied so that the latter not only tightens the two stretches of the band upon one another but also tightens the stem of adapter 7 upon one of the stretches, thus more firmly uniting the two adapters into one structural unit. As appears from Figure 8, the seat 17 of the second adapter may be brought into alignment with the seat 10 of the first adapter and may be disposed on the opposite sides of the frame, so that the two seats cooperate in forming a broader supporting surface for the arrow.

It is apparent that upon proper manipulation of the wing nuts 13 and 16 the unit as a whole may be retracted to bring the two arrow seats into inactive position.

I claim:

1. An arrow adapter for a sling shot frame having a body section and spaced legs projecting therefrom, the adapter comprising an elongated stem having a recess on one end thereof shaped to form an arrow rest and having a longitudinal slot therein, and means extending through the slot for securing the stem upon the side of the body section with freedom of adjustability to position the arrow rest with respect to the legs, with a band fixed on the legs and means for securing the stem upon the band.

2. An arrow adapter for a sling shot frame having a body section and spaced legs projecting therefrom, the adapter comprising an elongated stem having a recess on one end thereof shaped to form an arrow rest and having a longitudinal slot therein, and means extending through the slot for securing the stem upon the side of the body section with freedom of adjustability to position the arrow rest with respect to the legs, with a band slidable on the legs and means for securing the stem upon the band, operable for tightening the band upon the legs.

3. An arrow adapter for a sling shot frame having a body section and spaced legs projecting therefrom, the adapter comprising an elongated stem having a recess on one end thereof shaped to form an arrow rest and having a longitudinal slot therein, and means extending through the slot for securing the stem upon the side of the body section with freedom of adjustability to position the arrow rest with respect to the legs, with a band slidable on the legs and means for securing the stem upon the band, operable for tightening the band upon the legs, the

60

band having a second rest mounted thereon adapted for alining with the first rest.

4. An arrow adapter for a sling shot frame having a body section and spaced legs projecting therefrom, the adapter comprising a band slidable on the legs and having an arrow seat mounted thereon, and means for securing the band on the legs in adjusted position.

5. An arrow adapter for a sling shot frame having a body section and spaced legs projecting therefrom, the adapter comprising a band slidable on the legs and having an arrow rest mounted thereon, a screw extending through opposing stretches of the band midway of the legs, and a nut on the screw operable for drawing the opposing stretches toward one another for securing the band upon the legs against sliding motion.

6. An arrow adapter for a sling shot frame having a body section and spaced legs projecting therefrom, the adapter comprising a band slidable on the legs and having an arrow rest mounted thereon, a screw extending through opposing stretches of the band midway of the legs, and a nut on the screw operable for drawing the opposing stretches toward one another for securing the band upon the legs against sliding motion.

20 7. An arrow adapter for a sling shot frame having a body section and spaced legs projecting therefrom, the adapter comprising a band slidable on the legs and having an arrow rest mounted thereon, a screw extending through opposing stretches of the band midway of the legs, and a nut on the screw operable for drawing the opposing stretches toward one another for securing the band upon the legs against sliding motion, with means secured upon the body section of the frame and engageable by the screw for steadyng the arrow rest.

25 8. An arrow adapter for a sling shot frame having a body section and spaced legs projecting therefrom, the adapter comprising a band slidable on the legs and having an arrow rest mounted thereon, a screw extending through opposing stretches of the band midway of the legs, and a nut on the screw operable for drawing the opposing stretches toward one another for securing the band upon the legs against sliding motion, with means secured upon the body section of the frame and engageable by the screw for steadyng the arrow rest, the latter means including a second arrow rest located for lining up with the first rest when the said means is engaged by the screw.
